PAPER GUIDE AND CUTTER ATTACHMENT FOR BUILT-IN TOILET PAPER ROLL FIX- TURES

Henry D. Noel, New York, N. Y.

Application March 31, 1942, Serial No. 436,952

3 Claims. (Cl. 242—55.5)

This invention relates to paper roll appliances and more specifically to a toilet paper roll attachment for built-in fixtures for facilitating the tearing off of a length of paper and for guiding the paper as it is pulled from the roll.

In the conventional recessed built-in toilet paper roll fixture, the free end of the paper is often inaccessible for pulling upon which requires manual turning of the roll to expose the same for grasping. In addition to the aforementioned annoyance, the paper may be unevenly torn intermediate the perforations which divide the same into sheets and which leaves the free end of the roll in an unsightly condition. It is therefore the primary object of the invention to provide a paper roll attachment which will eliminate the above referred to conditions.

Another feature of the invention resides in an attachment for facilitating the guiding and tearing away of a length of toilet paper from a roll, and which may be installed upon built-in toilet paper roll fixtures without any alterations thereto.

Other features of the invention are to provide a combined toilet paper roll guide and cutter which is easily installed; which may be made in different colors to match the paper roll fixture or tile so as not to be conspicuous and detract from the appearance of the toilet room in which it is installed; and which is simple and inexpensive of construction.

Other features of construction will become apparent as the following specification is read in conjunction with the accompanying drawing, in which:

Figure 1 is a perspective view of the combined toilet paper roll guide and cutter per se, the paper roll holder being shown in dotted lines.

Figure 2 is a vertical sectional view through a recessed built-in toilet paper roll fixture with the roll guide and cutter attachment associated therewith, the roll holder being shown in full lines and the roll of paper in dotted lines.

Figure 3 is a vertical sectional view on the line 3—3 of Figure 2.

Figure 4 is a detail side elevational view of a modified form of roller receiving slot.

Referring to the drawing by reference characters, the numeral 10 designates the toilet roll attachment in its entirety which may be constructed of metal, but preferably of a plastic so that it may be made in different colors without any additional painting operation. The attachment 10 is substantially frame shape and includes a pair of opposed angularly bent end mem-

bers or legs 11 and 12, having axially aligned openings 14 and 15 respectively.

Formed integral with the upper ends of the arms 11 and 12 are like forwardly extending arcuate extensions 19—19 which are connected by a cutter bar 20 which is provided with serrations or pointed teeth 21. Disposed beneath the bar 20 in spaced relation thereto is a paper guide plate 22 having its front edge disposed a substantial distance inwardly of the plane of the serrated cutting edge 21, the ends of the plate 22 being integral with or fixedly connected to the extensions 19—19. The front edge of the plate 20 is cut away as at 23 to facilitate the reaching under the bar 20 to grasp the free end of the paper when it is desired to pull a length of paper from the roll in a manner to be herein-after more specifically described.

The top and bottom portions of the legs 11 and 12 have substantially V-shaped aligned notches 24 extending inwardly from their rear edges, while the lower portions of said legs are provided with similar notches 25. The notches 24 and 25 respectively engage the upper and lower exterior corners of a recessed built-in toilet paper roll fixture A when the attachment is in use as set forth in Figure 2.

The space between the legs 11 and 12 is slightly greater than the width of the roll of paper R so that the roll is free to rotate upon the roll holder 17. The space between the plate 22 and the bar 20 constitutes a guide space 26 through which the free end B of the roll of paper R is threaded.

In practice, the roll holder 17 with the roll of paper R thereon is inserted between the legs 11 and 12 and the trunnions 16—16 inserted through the aligned openings 14 and 15, it being understood that the roll holder 17 is provided with a spring actuated plunger trunnion which is pushed inwardly to a retracted position. After the attachment 10 is connected to the roll holder 17 and roll of paper R, the same is inserted into the recess of the fixture A so that the top and bottom of the angular legs extend in a forward direction. When the trunnions 16—16 engage their bearing seats in the opposed side walls of the recessed fixture A, the notches 24 and 25 respectively engage and receive the top and bottom corner edges of the recess. Thus, as the roll of paper is rotated to provide a length of paper to be torn free, the attachment 10 remains stationary. The free end B of the roll of paper passes through the guide space 26 and rests upon the plate 22. To receive a length of paper from

the roll R, the operator grasps the free end B and pulls outwardly thereon until the desired length extends from the serrated edge 21, whereupon the length of paper is torn by an upward and cross pull by the operator to cause an even cutting of the paper by the serrated edge. Due to the fact that the front edge of the plate 22 is rearwardly offset with respect to the cutting edge 21 there will always be a short length of paper forwardly of the plate 22 which may be grasped by an operator for subsequent pulling and tearing off lengths of paper from the roll. The free end of the paper is concealed until the operator reaches under the front of the bar 29, grasps the same and pulls outwardly thereon.

In Figure 4 of the drawing, I have illustrated a slight modification in which the legs 14 and 12 are provided with substantially L-shaped slots 13 which open through the rear edge. By this construction the attachment 10 may be slipped onto the trunnions of roll holders which are provided with fixed trunnions. The trunnions seat in the closed ends of the slots.

While I have shown and described what I consider to be the preferred embodiment of my invention, I wish it to be understood that such changes in construction and design as come within the scope of the appended claims may be resorted to if desired without departing from the spirit of the invention.

Having thus described the invention, what I claim as new and desire to secure by Letters Patent of the United States is:

1. A paper cutter and guide device for attachment to a built-in recessed toilet paper roll fixture comprising a pair of like spaced apart opposed angular shape end members having aligned openings for receiving the ends of a paper roll holder, a brace bar connecting the lower ends of the end members, like forwardly extending arcuate shape extension portions formed integral

with the upper ends of the end members, a cutter member connected to and bridging the space between said extension portions and having a front cutting edge, and a guide member connected to and bridging the space between the extension portions and disposed beneath and in relatively close spaced relation to said cutter member, the space between said cutter member and guide member constituting a guide passage for the free end of a roll of toilet paper when the device is in use.

2. A paper cutter and guide device as set forth in claim 1, in which the rear edges of the end members are notched adjacent their upper and lower ends for interfitting engagement with the front top and bottom corner edges of recessed built-in toilet roll fixture.

3. A paper cutter and guide device for attachment to a built-in recessed toilet paper roll fixture comprising a pair of spaced apart opposed angular shape end members having aligned openings for receiving the ends of a paper roll holder, forwardly extending extension portions rigidly connected to the upper ends of the end members, a cutter member connected to and bridging the space between said extension portions and having a front cutting edge, and a guide member connected to and bridging the space between the extension portions and disposed beneath and in relatively close spaced relation to the cutter member, the space between said cutter member and guide member constituting a guide passage for the free end of a roll of toilet paper when the device is in use, said end members being notched at their upper and lower ends inwardly from the rear edges thereof for interfitting engagement with the front top and bottom corner edges of a recessed built-in toilet roll fixture.

HENRY D. NOEL.
